CIRCUITS FOR THE PRODUCTION OF PURE MODULATED CARRIER WAVES

Filed Sept. 18, 1923

Inventor:
Roy E. Coram
by E. Griggs Atty.

UNITED STATES PATENT OFFICE.

ROY E. CORAM, OF NEWARK, NEW JERSEY, ASSIGNOR TO WESTERN ELECTRIC COMPANY, INCORPORATED, OF NEW YORK, N. Y., A CORPORATION OF NEW YORK.

CIRCUITS FOR THE PRODUCTION OF PURE MODULATED CARRIER WAVES.

Application filed September 18, 1923. Serial No. 663,334.

To all whom it may concern:

Be it known that I, Roy E. CORAM, a citizen of the United States, residing at Newark, in the county of Essex, State of New Jersey, have invented certain new and useful Improvements in Circuits for the Production of Pure Modulated Carrier Waves, of which the following is a full, clear, concise, and exact description.

10. This invention relates to modulating circuits and more particularly to circuits for the production of pure modulated carrier waves.

The ordinary circuit for modulating a carrier wave in accordance with a signal or 15 other control wave produces a complex resultant wave comprising a pure modulated wave and an unmodulated component of the carrier wave frequency. It is frequently desirable to produce a modulated carrier 20 wave having no unmodulated carrier frequency component. An example of a circuit for accomplishing this purpose is the balanced modulator of J. R. Carson Patent No. 1,449,382, March 27, 1923. It is an object of 25 the present invention to provide a circuit for producing pure modulated waves with the simplest possible apparatus.

According to the present invention, signal or other modulating waves are impressed 30 upon the input circuit of an electron discharge device of a well-known three-element type, preferably highly evacuated. A source of carrier waves is connected to the discharge electrodes and to a path including 35 an equivalent impedance in such manner as to supply alternating currents in parallel to the variable impedance between the discharge electrodes and to a constant impedance. A signal transmission circuit is 40 differentially associated with the alternating current paths including the discharge electrodes and the fixed impedance element and accordingly receives no current as long as the impedance balance is maintained. When, 45 however, the impedance of the discharge device is varied by incoming signals, the balance is disturbed and carrier waves corresponding to the resulting difference currents in the two alternating current paths, 50 are supplied to the outgoing transmission circuit.

The novel features which are considered 55 characteristic of the invention are pointed out with particularity in the appended claims. The invention itself, however, both

as to the details of its organization and its mode of operation will be best understood by reference to the following description taken in connection with the accompanying drawing in which Fig. 1 illustrates a radio telephone system embodying the invention, and Fig. 2 illustrates a modification of the modulator circuit of Fig. 1.

Referring to Fig. 1 a source of speech or other control currents represented by the microphone 1, in series with a battery 2, is associated by means of the transformer 3 with the input circuit of a three-element electric discharge device 4 of well-known type. Connected in series in the input circuit of the grid or impedance control element 5 and the cathode 6, are the secondary of transformer 3, a choke coil 7 and a polarizing battery, 8 for maintaining the normal operating potential of the grid at a desired value with respect to that of the cathode. A source 9 of space current, in series with a choke coil 10 of high impedance to alternating currents of carrier frequency, is connected between cathode 6 and anode 11 to supply space current. Source 12 of carrier current is associated, by means of a potentiometer 13 and a transformer 14, with two parallel alternating current circuits which traverse respectively, the space discharge path of device 4, and a constant impedance 15. Each of these circuits includes a large blocking capacity element 16. The two alternating current circuits or branches are connected by means of three-winding transformers 17 to a transmission circuit 18, in such manner as to induce opposing electromotive forces therein. The circuit 18, which is coupled to a transmission circuit 19 by transformer 20, includes a band filter 21 which passes with low and substantially uniform attenuation, frequencies corresponding to one side band of the modulated carrier wave and substantially extinguishes currents outside this frequency range.

In an actual operation of this circuit, the device 4 consisted of a standard telephone repeater tube. This tube was operated with a negative grid potential impressed by means of source 8, so that its alternating current impedance between the cathode and anode was of approximately 6000 ohms. The condenser 16 in the alternating current path between the cathode and anode had a capac- 110

ity of one microfarad, and the condenser 16 in the other branch was of like capacity. It was found in operation of this device, that without the inductance device 7, there was 5 a tendency for an alternating electromotive force of the carrier frequency to be induced in the grid circuit leads, and to be impressed upon the input elements of the discharge device 4, thus giving rise of an amplified carrier frequency current in the alternating current plate circuit path, in addition to that directly impressed on this path by source 12. To prevent this effect, the element 7 having inductance of approximately 10 henrys, was inserted in the grid circuit. The potentiometer 13 enables the alternating electromotive force supplied to the discharge device to be made such that the device is not overloaded, thus making 15 it possible to eliminate, to a large degree, a distortion giving rise to resulting undesired frequency components which will not be neutralized by the current through the fixed impedance.

20 25 The band filter 21 may be designed in accordance with well-known principles, as outlined in United States patent to G. A. Campbell, No. 1,227,113, May 22, 1917. The circuit 19, although illustrated as an antenna, may obviously be a transmission conductor of any sort, and the transformer 20 may be replaced by any suitable coupling.

25 30 In operation, the alternating currents induced in the two paths traversing space discharge device 4 and the impedance element 15 are normally equal and in phase. In consequence of the differential connection of the transmission circuit 18, the electromotive forces induced therein are oppositely directed and neutralized. When speech or other signal control currents are impressed by means of the transformer 3 upon the input circuit of device 4, thus varying its impedance, the current in this 35 40 branch alternately increases and diminishes, thus destroying the balanced condition with respect to circuit 18. There will accordingly be impressed in circuit 18, a carrier wave of the frequency of source 12, the amplitude of which is proportionate to the variation currents impressed upon the input circuit of device 4. The modulated carrier wave supplied in the transmission circuit 18 comprises, as is well known, an upper side 45 50 band and a lower side band, equally removed in frequency, from the frequency of the carrier source 12. In order to improve the quality of signals received at the receiving station and to economize in the 55 60 frequency range of the waves transmitted, the filter 21 is provided to transmit one of the side bands and to eliminate waves of other frequencies including the other side band. To an extent, this filter 21 may serve 65 70 to suppress any unmodulated component of

carrier frequency, should the impedance fail to match the normal impedance of device 4. However, the percentage frequency difference between the carrier frequency and the contiguous frequencies of the side band 70 to be transmitted, is, in general, small, and it is therefore very desirable to make the balance as accurate as possible. For this purpose, the resistance 15 may preferably be variable.

75 Fig. 2 shows a similar arrangement with elements similarly designated. A coupling circuit between the signal source and the input circuit of tube 4 includes a potentiometer 31 to regulate the magnitude of the modulating current impressed thereon. To generate carrier current, there is provided a vacuum tube oscillator comprising a space discharge device 32 in the plate filament circuit of which there is included a closed oscillatory circuit 33, tuned to the desired carrier wave frequency and coupled by transformer 34 in feed-back relation to its input circuit. The cathode of oscillator 32, preferably heated from the source 35, is in 80 series with the cathode of modulating device 4. Space current is supplied to the discharge devices 4 and 32 from the common source 9, through the choke coils 10 and 36 respectively, which prevent by-passing of 85 carrier frequency current to the space current source 9. A resistance 37 in the alternating current plate circuit path of the oscillator is provided to stabilize the oscillations of the oscillator and prevent overloading. A potentiometer resistance 38 is connected between the cathode of discharge device 4 and the midpoint of the windings of transformer 17 in the same relative position as the secondary winding of transformer 14 100 of Fig. 1. The oscillator 32 impresses an alternating electromotive force between the common cathode connection and the contact of a variable tap 39 on the potentiometer resistance 38. A blocking condenser 40 of 105 large capacity in series with the tap 39 prevents transmission of direct current through the resistance element 38. This element is preferably of large impedance as, for example, 40,000 ohms. The operation of this 110 circuit is, in general, the same as that of the circuit of Fig. 1.

115 It will be readily appreciated that this circuit provides a very simple and economical arrangement for modulated carrier wave transmission where the unmodulated carrier frequency component is to be eliminated. Although retaining the desirable characteristics of vacuum tube modulators, a single tube only is required for the modulating operation. This results in low cost and upkeep, and simplicity of adjustment.

120 What is claimed is:

1. In combination, a work circuit, a source 125 of alternating current, a variable electric

- discharge impedance element, a constant impedance of substantially equivalent magnitude, and two circuits differentially connecting said source to said work circuit and including respectively said variable electric discharge impedance and said constant impedance, whereby alternating current is supplied to said work circuit only during and in proportion to variations in said impedance.
2. A modulating system comprising a source of carrier waves, a two-path circuit connected thereto, one path of which includes a variable thermionic impedance, and the second path of which includes a constant impedance simulating in magnitude the normal impedance of said first-mentioned path, and means for deriving from said circuit a current proportionate to the difference between the currents in the two paths.
3. In combination, a source of alternating current, a three-element electric discharge device having discharge electrodes and an impedance control element, a metallic circuit having an impedance comparable in magnitude to that between said discharge electrodes, means for impressing an alternating electromotive force from said source upon said discharge electrodes and a like electromotive force upon said circuit, a work circuit, and means for impressing upon said work circuit an electromotive force corresponding to the difference between the alternating current in said impedance circuit and that between said discharge electrodes.
4. In combination, an electric discharge device having discharge electrodes and means for controlling the impedance therebetween, a closed metallic path of predetermined impedance, a source of alternating current associated with said discharge device and said path to supply current thereto in parallel, and a work circuit differentially connected to said device and said path whereby differences of current traversing
- said device and said path produce a resultant current in said work circuit.
5. A system comprising an electric discharge device having discharge electrodes and means for controlling the impedance therebetween, a source of space current for said device, a two-branch circuit including said discharge device in one branch and a constant impedance equivalent to the normal impedance of said device in the other branch, a common source for supplying alternating current to both of said branches, and a work circuit to which said branches are connected in opposition whereby current is supplied to said work circuit only when the impedance controlling means changes the impedance of said device from its normal value.
6. A signal system comprising a source of signaling currents, a source of carrier currents, an electric discharge device having an anode, a cathode, and an impedance control element, an input circuit associated with said source of signaling current and connected to said cathode and impedance control element, a second circuit connected with said cathode and anode and associated with said source of carrier waves, a path of high impedance to carrier current and including a space current source connected between said cathode and anode, an element, having a constant impedance equivalent to the normal alternating current impedance between said cathode and anode, connected to said source of carrier waves, and a signal transmission circuit connected in energy transfer relation with the alternating current circuits including said electric discharge device and said impedance element respectively.
- In witness whereof, I hereunto subscribe my name this 14th day of September A. D., 1928.

ROY E. CORAM.
